UNITED STATES PATENT OFFICE

1,986,170

DIRECTION FINDER

Cris W. Wiegand, Chicago, Ill.

Application December 5, 1932, Serial No. 645,785

3 Claims. (Cl. 33—222)

This invention relates to novel improvements in direction finders.

One of the main objects of this invention is to provide a direction finder of a novel construction which renders it highly efficient and at the same time inexpensive.

Another object is to provide a direction finder having its rotary magnetic bar or pointer so mounted that the center of the magnetic zone of one of its poles is placed substantially on the axis of rotation of the finder, whereby said zone and pole are impounded and rendered ineffective, while the other pole alone is free to function unhampered by the opposite pole.

Another object is to provide such a direction finder wherein the magnetic bar or pointer may be readily and interchangeably mounted, so that this bar can be quickly set to point either toward the north or toward the south, whichever may be deemed preferable at the time.

These and other objects and advantages will become apparent from the following description, taken in connection with the accompanying drawing, in which the invention is shown in its preferred forms, it being understood that various other arrangements and forms of construction may be resorted to for carrying out the objects and purposes of this invention.

In the drawing:

Fig. 1 is a plan view of my invention shown in one of its preferred forms of construction.

Fig. 2 is an enlarged vertical sectional view thereof, taken on line 2—2 of Fig. 1.

Fig. 3 is an enlarged vertical cross-sectional view, taken on line 3—3 of Fig. 2.

Fig. 4 is a plan view of the magnetized bar or needle used in this invention, the zones of magnetic influence of its poles being indicated.

Fig. 5 is an elevational view, partly broken away, showing my invention in a modified form, with the bar suspended by a thread.

In my invention, in either of its forms, the magnetic bar or needle is mounted so that one of its poles is confined while the other pole alone is free to function, unhampered by the confined pole, and thus enabling it to operate with increased efficiency. The construction is so arranged that the needle may be readily reversed, and either pole may be confined leaving the opposite one or the selected pole alone free.

In the form shown in Figs. 1 to 4 of the drawing my novel direction finder comprises a magnetized bar or needle 10 of paramagnetic material which is provided with a positive pole 11 at one end and a negative pole 11' at the other. This

bar is provided with a perforation 12 adjacent each end, and each of these perforations is placed substantially and as nearly as possible at the center of the magnetic zone of influence of the pole, as indicated in Fig. 4 by the broken curved line 13 at each end of the bar.

The means for supporting the bar or needle comprises a sleeve or casing 14 having a flat sleeve portion 15 at one end for receiving either end of bar 10 slidably and removably therein.

Said sleeve has a cap 16 on its top containing a jewel 17 in its upper end, which rests rotatably on the top end of a spindle or spin-shaft 18 extending through one of the perforations 12 and through suitable openings provided in the sleeve.

Means for balancing magnetic bar 10 comprises a bar or arm 21 which has one end mounted in a sleeve portion 22 on sleeve 14, opposite sleeve portion 15, so that said bars 10 and 21 are substantially aligned longitudinally. This arm consists of a non-magnetic material, such as bakelite, compressed rubber, aluminum, or some other suitable non-magnetic material.

To provide for a very accurate balancing of the arm 21 and bar 10 on shaft 18, a weight or band 23 is preferably mounted on arm 21, so as to be slidably adjustable thereon.

In this form a housing or casing 25 is provided for supporting and protecting the finder. Spin-shaft 18 is mounted in the center of its base member 26, and a crystal or transparent cover 27 is mounted at the top of the casing, for example as indicated in the drawing.

This magnetic bar 10 is preferably also provided with a perforation 28 at its middle or neutral section, besides perforations 12 of the poles, so that spindle 18 can be passed through said perforation 28 and the bar can be mounted centrally in sleeve 14, while arm 21 and weight 23 are omitted; and as said sleeve is constructed so as to balance on spindle 18, this device is also adapted to be operated like the usual compass needle.

As the bar or needle 10 is removably and interchangeably mountable with either of its ends in sleeve portion 15, and as the perforation 12 of the confined pole, wherethrough shaft 18 extends, is positioned substantially centrally of its magnetic zone of influence, said pole with its magnetic zone will be confined, thereby leaving the other pole alone free to function, unhampered by said confined pole and with increased efficiency. With this reversibility the bar can be readily mounted so that either its north-seeking

pole or its south-seeking pole is placed free to operate, whichever may be deemed most expedient at the time.

In Fig. 5 of the drawing my invention is illustrated in a modified form. The magnetized bar 10' therein is interchangeably mountable with either of its ends in the portion 15' of the sleeve member 14', in the same manner as in the preceding form, and the balancing arm 21' has one end mounted in the portion 22' of said sleeve, while a weight 23' is adjustably mounted on said arm.

In this form a yoke or eye member 30 is provided on top of sleeve 14', whereto a cord or thread 31 is attached which is preferably in the form of a silk thread, the same being suspended from the top of a transparent cupola or dome 32 provided with a suitable base 33. Said thread is readily secured in a suitable opening provided in the top of said dome, by means of a wedge element 34 or the like.

In this form of my invention I have found that the bar and arm oscillate freely on the thread and that said thread remains perfectly vertical and constitutes a perfect axis of rotation, in the nature of a perfect plumb bob, without any deviations or swinging in circles, as is generally the case with the usual plumb bobs.

I have illustrated two of the several forms of this invention herein; and it is quite apparent that it is well adapted to be utilized in various other forms, as for use on a balloon or on ship-board, by mounting it in suitable gimbals or binnacle; and it may also be readily adapted for use as an inclinometer.

I claim:

1. A direction finder consisting of a straight bar of paramagnetic material provided with a positive pole at one end and a negative pole at the other end, a balancing arm extending beyond one end of said bar and substantially aligned therewith, a sleeve containing a pair of sockets, one for removably receiving one end of said arm and the other for interchangeably receiving either

end of said bar so as to have either pole readily and interchangeably connected with said arm while the other pole is free, means rotatably supporting said sleeve for pivotal movement about a vertical axis, and means adjustable on said arm for accurately balancing it and the bar to rotate in a horizontal plane, the axis of rotation of the finder extending substantially through the center of the magnetic zone of the pivoted pole thereby impounding it and leaving the other pole free to rotate about the pivoted pole.

2. A direction finder consisting of a straight bar of magnetized metal having a positive pole at one end and a negative pole at the other, there being a perforation provided in the center of the magnetic zone of each pole adjacent each end of the bar, a balancing arm of non-magnetic material extending from one end of the bar, a sleeve removably supporting one end of the arm and the other end of the sleeve being adapted to have either end of the bar interchangeably mounted therein, and pivoting means including a cap mounted on said sleeve and a pivot pin extending through the perforation in the pole into said cap, thereby supporting the bar and arm to rotate on an axis extending through the center of the magnetic zone of the connected pole to impound the same and leave the other pole free to rotate thereabout.

3. A direction finder consisting of a magnetized straight metal bar provided with a positive pole at one end and a negative pole at the other, a balancing arm of non-magnetic material extending beyond one end of said bar and aligned therewith, a sleeve removably mounting one end of said arm and in the other end of the sleeve interchangeably mounting either end of said bar, and means including a casing having a thread suspended centrally therein which has its lower end connected to said sleeve, whereby the bar and arm are rotatably supported so that the axis of rotation passes through the center of the magnetic zone of the bar's attached pole while its other pole is free to rotate thereabout.

CRIS W. WIEGAND.
